United States Patent Office

Des. 193,709
Patented Oct. 2, 1962

193,709

PANTY GIRDLE OR SIMILAR ARTICLE

Herbert Bromberg, Whitestone, N.Y.
(150 Henry St., Freeport, N.Y.)

Filed Dec. 19, 1961, Ser. No. 67,964

Term of patent 3½ years

(Cl. D20—2)

FIG. 1

FIG. 2

FIG. 1 is a front perspective view of a panty girdle embodying the invention; and

FIG. 2 is a rear perspective view thereof.

I claim:

The ornamental design for a panty girdle or similar article, substantially as shown.
